UNITED STATES PATENT OFFICE.

CARL SCHINKE, OF ST. LOUIS, MISSOURI, ASSIGNOR TO THE ST. LOUIS IRON AND MACHINE WORKS, OF SAME PLACE.

VALVE-GEAR FOR STEAM-ENGINES.

SPECIFICATION forming part of Letters Patent No. 280,672, dated July 3, 1883.

Application filed March 26, 1883. (No model.)

To all whom it may concern:

Be it known that I, CARL SCHINKE, of St. Louis, Missouri, have made a new and useful Improvement in Valve-Gear for Steam-Engines, of which the following is a full, clear, and exact description, reference being had to the annexed drawings, making part of this specification, in which—

Figure 1 is a side elevation of an engine having the improvement; Fig. 2, a view in perspective of the cam and parts immediately therewith connected; Fig. 3, another perspective view of the parts shown in Fig. 2; Fig. 4, a vertical section of the valve-chest, the valve about to open; Fig. 5, a section of the valve-chest, the valve being as when the governor-arm is in the position of Fig. 7; Fig. 6, a side elevation, showing the position of the eccentric when the crank is on the dead-center; Fig. 7, a similar elevation, but the governor-arm being raised; Fig. 8, a similar elevation, the eccentric being turned around one-quarter of a revolution, the governor-arm being at the center of its movement; Fig. 9, a similar elevation, the eccentric being turned around one-half a revolution, the governor-arm being in the same position as in Fig. 8.

The same letters of reference denote the same parts.

30 The present invention relates to the valve-gear of the engine.

A represents a steam-engine in which the improvement is embodied.

A' represents the engine-cylinder, and A² the main shaft.

B represents an eccentric fastened to the main shaft, and B' the eccentric-strap. The strap has two levers, C C', jointed to it at c c', respectively. These levers in turn are connected by the link D, the link being jointed at its ends to the levers. The levers thus connected can be moved together upon the bearings c c', and as indicated by the positions shown in Figs. 6, 7, 8, 9, respectively.

40 E represents the valve-rod for operating the live-steam valves. It is at one end jointed to the link D and at the other end to the rod E', which rod in turn is jointed to the crank F. The links G G' connect the crank F with the 45 cranks H H', respectively, of the valve-shafts

I I', respectively. The reciprocation of the rod E therefore causes the shafts I I' to rotate reciprocatingly and to open and close the circular valves J J', Figs. 4, 5, accordingly.

The invention has especial relation to the 55 means described for connecting the eccentric and valve-rod.

K represents a rod leading from the link D and valve-rod E to a lever, L, connected with the governor M, the lever L being pivoted at 60 l to the governor-standard m, and at l' being jointed to the governor-valve stem m'. The movement of the valve-stem m' therefore causes the link D and the parts thereto joined to be lifted and lowered, as shown in the various 65 positions of Figs. 6, 7, 8, 9. When the parts have been thus lifted so as to bring the valve-rod E in line with the throw of the eccentric, as in Fig. 7, the movement of the valves J J' is less than when the valve-rod is below the 70 line of the throw, as in Figs. 6, 8, 9. In the last-named case the valves cut off later than in the first-named case; but when the speed of the engine increases, the governor acts to lift the valve-rod toward the governor, and 75 the valves cut off later.

To keep the eccentric-strap suitably in place, and at the same time provide for a limited vibration of the eccentric strap upon the main shaft, an arm, N, is journaled at its lower end 80 to a fixed bearing, n, and at its upper end the arm is jointed to the eccentric-strap at n', Figs. 2, 3. The diaphragm yields sufficiently to the steam-pressure to balance the valve, and the knife-edge enables the valve to be 85 moved with little or no friction.

The rod R, which is jointed to the eccentric-strap, is for operating the exhaust-valves. (Not shown.)

I claim—

1. The combination of the shaft A², the eccentric B, the strap B', the levers C C', the link D, the rod E E', the crank F, the links G G', the cranks H H', and the valves J J', substantially as described.

2. The combination of the shaft A², the eccentric B, the strap B', the levers C C', the link D, and the valve-rod E, substantially as described.

3. The combination of the shaft A², the ec-

centric B, the strap B', the levers C C', the link D, the valve-rod E, the rod K, the lever L, and the governor M, substantially as described.

5 4. The combination of the shaft A², the eccentric B, the strap B', the levers C C', the link D, the valve-rod E, the rod K, the lever L, the governor M, the arm N, and the valves

J J', substantially as described, and for the purpose set forth.

Witness my hand this 16th January, 1883.

CARL SCHINKE.
